UNITED STATES PATENT OFFICE.

JAMES H. MASON, OF NEW YORK, N. Y.

DESIGN FOR AN ELECTRIC-ARMATURE MOUNTING.

SPECIFICATION forming part of Design No. 32,004, dated December 19, 1899.

Application filed November 7, 1899. Serial No. 736,196. Term of patent 7 years.

To all whom it may concern:

Be it known that I, JAMES H. MASON, a citizen of the United States, residing in the borough of Brooklyn, in the city of New York, county of Kings, and State of New York, have 5 invented and produced a certain new and useful Design for Electric-Armature Mountings, of which the following is a specification.

This design appertains particularly to the 10 mountings for the armatures of small fan-motors, although it is obviously applicable to larger devices.

My invention is illustrated in the accompanying drawings, wherein—

15 Figure 1 is a side view, Fig. 2 is a front view, and Fig. 3 is a rear view, of an electric-armature mounting containing the essentials of my invention.

In the drawings a field-magnet 1, having 20 windings 2, is provided with poles 3, to the outer ends of which is fixed a rigid cross com-

posed of a vertical part 4 and a horizontal part 5. On the extremities of the horizontal part of the cross are the supports 6, to which may be attached the necessary commutator- 25 brushes.

At 7 is shown the outer bearing of the armature, the field-magnet itself serving to support the other end of the armature-shaft.

The essential features of my invention are 30 a field-magnet having its poles extended at right angles to the wound portion, a cross fixed at the outer extremities of said poles, and brush-supports and armature-bearings on said cross.

35 What I claim is—

The design for electric-armature mounting substantially as shown and described.

JAMES H. MASON.
